TAPE RECORDER

Takeo Sho, Kanagawa-ken, and Motoya Shiroswa,
Tokyo, Japan, assignors to Tobishi Electronic In-
dustries, Ltd., Tokyo, Japan

Filed Nov. 8, 1967, Ser. No. 9,322

Term of patent 14 years

(Cl. D26—14)

FIG. 1

FIG. 3

FIG. 2

FIG. 4

FIG. 5

FIG. 6

FIG. 7

FIG. 8

FIG. 1 is a front perspective view of a tape recorder showing our new design;

FIG. 2 is a left end elevation thereof;

FIG. 3 is a front elevation thereof;

FIG. 4 is a top plan view thereof;

FIG. 5 is a right end elevation thereof;

FIG. 6 is a rear elevation thereof;

FIG. 7 is a bottom plan view thereof;

FIG. 8 is a front perspective view similar to FIG. 1 with the panel member in a partially opened position.

We claim:

The ornamental design for a tape recorder, substantially as shown and described.
